UNITED STATES PATENT OFFICE.

EARL PORTER WETMORE, OF TOLEDO, OHIO, ASSIGNOR TO THE STERLING CORK &
SEAL COMPANY, OF TOLEDO, OHIO, A CORPORATION OF DELAWARE.

SEALING-HEAD FOR BOTTLE-CAPPING MACHINES.

986,333.

Specification of Letters Patent. Patented Mar. 7, 1911.

Application filed January 4, 1910. Serial No. 536,304.

To all whom it may concern:

Be it known that I, EARL P. WETMORE, of Toledo, Lucas county, Ohio, have invented a new and useful Improvement in Sealing-Heads for Bottle-Capping Machines, of which the following is a full, clear, and exact description, reference being had to the accompanying drawings, forming part of this specification, in which—

10 Figure 1 is a longitudinal vertical section of a sealing head embodying my invention and showing a bottle neck and cap in entering position; Fig. 2 is a similar view on same scale with the cap shown in nearly 15 its sealed position; Fig. 2^a is a detail view on a larger scale, illustrating the action of the dies upon a cap; Fig. 3 is a section on the line III—III of Fig. 1; Fig. 4 is a perspective view of the die carrier; and Fig. 20 5 is a perspective view of one of the dies. Fig. 6 is a sectional elevation illustrating generally one means for lifting a bottle to the action of the capping head.

My invention has relation to sealing heads 25 for bottle capping machines, and is designed to provide a novel and efficient head of this character, especially adapted for use with sealing caps having a substantially horizontal corrugated flange, which, in the 30 sealing operation, is to be bent downwardly into the vertical plane of the skirt of the cap, and the corrugations of the flange forced inwardly underneath the locking shoulder of the bottle.

35 The invention has more particular relation to the novel construction and arrangement of the dies for effecting this work.

The precise nature of my invention will be best understood by reference to the accompanying drawings, in which I have 40 shown the preferred embodiment thereof, and which will now be described, it being premised, however, that various changes may be made in the details of the construction

45 and arrangement of the various parts without departing from the spirit and scope of my invention as defined in the appended claims.

In these drawings, the numeral 2 designates the casing of the head, which is de-

5 signed to be secured in fixed position above the bed of the capping machine in the usual manner, the machine being provided with means of any approved character for raising the bottles into the head to effect the 5 sealing. This casing or shell has an enlarged interior chambered portion or head 3 at its lower end, in which are seated a plurality of radially movable segmental dies 4, 6 these dies being shaped at their inner ends 6 to make up a complete cylindrical die cavity, as clearly shown in Fig. 3. The die members are seated in a block 5, which is removably fitted within the lower portion 15 of the head; and which is formed with a 65 plurality of radial slots 6 to seat the dies. Each die is formed with an outwardly opening pocket 7 to seat a spring 8, the inner end of the spring seating against the inner wall 7 of the pocket, and the outer end seating in a screw plug 9. These screw plugs are threaded into a sleeve 10, which is threaded into the head and surrounds the die carrier 5, and has an inwardly extending annular flange 11 at its lower end, which forms a 7 bearing surface for the lower faces of the dies 4. The die carrier is formed with the shoulder at 12, which is arranged to be engaged by a stop lip or projection 13 on each die for the purpose of limiting the movement of the die. In this manner each die is capable of an independent limited radial movement against its spring.

14 is a rod or plunger, which extends vertically upward into the shell or casing 2, 85 being guided at 15 at its upper end, and having a surrounding flange 16 near its lower end, which normally seats downwardly against the upper face of the die carrier 5. The portion 14^a of this plunger 90 which is below the flange 16 extends downwardly through the die carrier and through the die cavity.

17 designates a relatively stiff coil spring seated around the upper portion of the 95 plunger between its upper guide and the flange 16, this spring being arranged to oppose upward movement of the plunger.

The lower portion of the head is formed by a separate member 18 having therethrough a conical guide opening 19 through which the bottle necks are elevated. This guide member is detachably secured to the head, preferably by means of a bolt 20 engaging corresponding lugs on the guide member and head, and also acting as a pivot on which the guide member can be swung. The guide member may be normally secured in place by a clip or latch device 21. This guide member is also cut away at its upper surface at one side as shown at 22 to form a space for the operation of a cap feeding device, which may be of any approved character.

24 indicates a bottle to be capped, and 25 one of the horizontally flanged sealing caps.

The operation is as follows:—The caps are successively fed into the position shown 20 in Fig. 1 by the action of the feeding devices, and the bottles are then elevated against the caps and the lower end of the plunger 14^a. This raises the plunger against the spring 17, and brings the horizontal 25 flange 26 of the cap into contact with the lower horizontal face of the dies. It will be noted that each of these dies has a horizontal lower face and a vertical inner face, and that the two faces are connected by the rounded 30 surfaces 4^a. The first contact of the dies with the horizontally extending flange 26 of the cap is at a point near the outer edge of such flange as shown in Fig. 2^a, thereby preventing any tendency of the dies to shear the 35 flange from the body or skirt of the cap, and also giving an effective bending leverage. As the cap is forced upwardly into these dies, to the position shown in Fig. 2, the flange is bent or wiped downwardly into substantially 40 the vertical plane of the skirt portion of the cap, as shown in Fig. 2. This, of course, causes the flange to assume an approximate 45 circle of considerably less diameter than its original diameter, and in assuming this position the corrugations naturally close and their upper end portions are forced inwardly underneath the usual locking shoulder on the bottle, thus giving a very secure and effective lock.

50 Owing to the fact that the bending pressure required to make the seal is almost wholly in a vertical direction, there is practically an entire absence of any inward pressure against the necks of the bottles of a 55 character to cause breakage. The dies being made in sections, capable of independent yielding movement, readily adapt themselves to irregularities in the form of the bottle neck, and also to variations in the sizes 60 of such necks, so that a perfect seal is produced notwithstanding such variations or

differences. The caps can also be made of relatively thin metal which will readily stretch and adapt itself to these differences and variations.

65

For convenience in removing the die carrier and dies from the head and handling them as one piece, the die carrier may be connected to the sleeve or bushing 10 by means of screws passing upwardly through the inwardly extending flange of the sleeve into the dies carrier, the perforations in the latter for these screws being shown at 27 in Fig. 4, and the screws being shown at 28 in Fig. 3.

70

Any suitable or usual means may be employed for lifting the bottles to the action of the capping head. I have indicated in Fig. 6, one such means, consisting of a vertically movable plunger A having a cross head at its lower end, which is actuated by a rotating cam B.

75

It will be obvious that various changes may be made in the details of construction and arrangement of the parts without departing from the spirit and scope of my invention. Thus, the die members may be differently shaped; the precise manner of their seating and of the seating of their springs may be changed; different forms of plungers may be employed, and various other changes 80 may be made.

85

What I claim is:—

1. In a sealing head for bottle capping machines, a casing or shell, a sleeve or bushing removably secured therein and having an inwardly extending annular flange at its lower end, a die seating block within said sleeve or bushing, said block having a plurality of radial die seating slots open at their lower ends, and a plurality of independently 95 movable dies seated in said slots and upon the upper face of said flange; substantially as described.

100

2. A capping mechanism, comprising a die composed of a plurality of members or sections having independent radial movement, their inner surfaces when closed forming a substantially continuous cylindrical die cavity, said members or sections also each having a substantially horizontal lower die face 110 to engage the flange of a sealing cap near the outer periphery thereof, together with means for effecting a relative movement of the dies and cap in the direction of the longitudinal axis of the said cavity, substantially as described.

115

3. A capping mechanism, comprising a die composed of a plurality of members or sections having independent radial movement, their inner surfaces when closed forming a 120 substantially continuous cylindrical die cavity, said members or sections also each hav-

ing a substantially horizontal lower die face to engage the flange of a sealing cap near the outer periphery thereof, the horizontal faces being connected with the inner and substantially vertical die faces by rounded corners to prevent shearing action on the flange of the cap, together with means for effecting a relative movement of the dies and cap in

the direction of the longitudinal axis of the die cavity, substantially as described.

In testimony whereof, I have hereunto set my hand.

EARL PORTER WETMORE.
